UNITED STATES PATENT OFFICE.

LOUIS WILKEN AND JOSEPH A. YOSTEN, OF COLUMBUS, NEBRASKA.

END-GATE FOR VEHICLES.

1,281,460.

Specification of Letters Patent. Patented Oct. 15, 1918.

Application filed March 25, 1918. Serial No. 224,696.

To all whom it may concern:

Be it known that we, LOUIS WILKEN and JOSEPH A. YOSTEN, citizens of the United States, residing at Columbus, in the county 5 of Platte and State of Nebraska, have invented certain new and useful Improvements in End-Gates for Vehicles, and we do declare the following to be a full, clear, and exact description of the invention, such as 10 will enable others skilled in the art to which it appertains to make and use the same.

This invention relates to end gates for vehicles, and it relates more particularly to an improved form of gate fastener.

15 One object of this invention is to dispense with the usual cross rods, chains, etc., that connect the walls of vehicle bed;

Another object is to provide a device of 20 this character which enables the end gate to prevent the walls of the vehicle bed from being pressed outward by the load;

Another object is to provide a device of 25 this character which prevents warping of the end gate;

Another object is to provide an efficient 30 fastening device which permits the end gate to be easily removed from its seat;

Another object is to provide for preventing 35 the end gate from working upward in its seat;

Another object is to prevent splitting of 40 the adjusting portions of the vehicle bed walls;

Another object is to provide a device of 45 this character which provides an efficient locking member and also provides handles whereby the end gate may be raised when it is unlocked.

Another object is to provide a device of 50 this character which is strong, durable, convenient, thoroughly practical, and which may be manufactured at a slight cost;

Other objects may become apparent to 55 persons who read the following details of description in connection with the accompanying drawings in which—

Figure 1 is an elevation disclosing the rear end of a vehicle body or bed provided with our improved end gate fasteners.

50 Fig. 2 is an elevation of one of our improved end gate fasteners applied to the rear end of a vehicle bed, this view being observed at right angles to Fig. 1.

Fig. 3 is a vertical sectional view along 55 the line 3—3 of Fig. 1, showing the end gate

fastener which is complementary to the one illustrated in Fig. 2.

Fig. 4 is a top plan view of the construction illustrated in Fig. 1.

Fig. 5 is an enlarged vertical sectional view 60 taken along the line 5—5 of Fig. 2.

Fig. 6 is a view illustrating a group of component elements of our improved end gate fastener.

Referring to these drawings in detail, in 65 which similar reference characters correspond with similar parts throughout the several views, the vehicle body or bed 7 is provided with the usual vertical side walls 8 having pairs of strips or vertical guides 70 9 between which the end gate 10 is normally seated.

The end gate may be of any usual or appropriate construction, and will not be described in detail. At each end of the end 75 gate 10 is secured one of our improved end gate fasteners, these end gate fasteners being complementary to one another, so that the description of one will suffice for both.

Each end gate fastener comprises an integral frame or bracket 11, a U-shaped guiding member 12, an apertured bar 13, a bolt 80 or locking member 14, a lever 15 and the rivets or other securing means whereby these parts are secured together and secured 85 to the end gate.

The frame 11 is formed integrally from a strip of sheet metal or a length of strap metal and comprises an apertured bar 16 and two U-shaped supporting elements 17. 90 The members 11, 12 and 13 are provided with aligned apertures through which rivets or bolts 18 extend for securing these three members together as a unitary frame structure. The bar 13 and guide 12 are provided 95 with aligned apertures 19 through which the bolt or locking member 14 is slidable. The bolt 14 has a key 20 therethrough, and a spring 21 is coiled around the bolt 14 between the key 20 and the bar 13, so as to 100 hold the bolt in its locking position.

The bar 13 is provided with pairs of apertured ears 22, and between the ears of each pair is mounted a roller or anti-friction element for a purpose presently described.

105 The lever 15 is provided with an aperture 23 through which the bolt 14 or locking element extends, and a key 24 retains the bolt within the aperture 23 of the lever which is moved outward by means of its handle 25. 110

One end of the lever 15 is provided with apertured ears 26, and the apertures of these ears register with the apertures of one pair of the ears 22 and have a pivot 27 extended therethrough, so that the lever 15 swings about the pivot 27 when the handle 25 is moved outward for unlocking the end gate.

The bar 16 is secured to the end gate by means of the bolts or rivets 28, and as this bar extends across the grain of the wood of the end gate, the latter is thus prevented from splitting or warping.

A combined reinforcing member and track 29 is secured in vertical position on each wall 8, and extends over the top and under the bottom of the wall so as to prevent splitting of the latter at this portion of the bed. Each strip 29 is apertured at 30 for the reception of the inner end of the adjacent bolt 14, thus coöperating with the latter in locking the end gate. Moreover, each member 29 constitutes a track along which the rollers 22^a travel when the end gate is being raised or lowered. In this connection, it will be seen that the U-shaped elements 17 provide efficient handles whereby the end gate may be raised when the load bears against the latter to such an extent that the handles 25 are less competent for effecting such raising of the end gate. Moreover by the provision of these U-shaped elements, the anti-friction elements are supported contiguous to the outer surfaces of the walls 8, and secure these walls against being pressed outward by the load in the bed.

Although we have described this embodiment of our invention very minutely, it is to be understood that our invention is not limited to these exact details of construction and arrangement of parts, but that we are entitled to make such minor changes as do not constitute a departure from the inventive idea disclosed in the foregoing description and appended claims.

What we claim as our invention is:

1. In combination with a wagon-box or body of the ordinary construction, in which pairs of vertical guides are provided on the inner surfaces of the side walls of the box, and a gate for closing the space between said side walls; a bracket for each of the two ends of the gate, and a locking element for each of these brackets, each of said brackets being secured to said gate and comprising an element adapted to extend around

an end of one of said side walls in such relation as to limit the separation of said walls, the locking elements combining with said brackets for releasably locking said gate in a predetermined position between said walls. 60

2. An end gate fastening device comprising a pair of U-shaped supporting elements, an apertured bar united with corresponding ends of said U-shaped supporting elements, means for securing the other ends of said U-shaped elements to an end gate, an apertured guiding member carried by said bar, a locking element slidably mounted in the apertures of said bar and guide, and means 70 for yieldingly holding said locking element in its locking position when attached to an end gate during use of the latter.

3. An end gate fastening device comprising a pair of U-shaped supporting elements, 75 an apertured bar united with corresponding ends of said U-shaped supporting elements, means for securing the other ends of said U-shaped supporting elements to an end gate, an apertured guiding member carried 80 by said bar, a locking element slidably mounted in the apertures of said bar and guiding member, a spring for moving said locking element in one direction, and a lever for moving said locking element in the 85 opposite direction.

4. The combination with a pair of spaced, vertical walls and a gate for closing the space therebetween, of a pair of frames each comprising a pair of U-shaped supporting 90 elements and a pair of apertured bars connecting the ends of said U-shaped supporting elements, means extending through the apertures of one of said bars of each frame for securing it to the end gate in such a position that the other bar of said pair is parallel with the adjacent vertical wall and spaced from the outer surface of the latter, a track on the outer surface of each wall, anti-friction elements carried by said other bar 100 of each of said frames in position to roll along one of said tracks, and means carried by each of said frames for detachably locking it to the adjacent one of said tracks. 95

In testimony whereof we have hereunto 105 set our hands in the presence of two subscribing witnesses.

LOUIS WILKEN.
JOSEPH A. YOSTEN.
